WEASAND SEPARATOR

William John Hincks, Norwood, Manitoba, Canada, assignor to Canada Packers Limited, St. Boniface, Manitoba, Canada

Application June 19, 1948, Serial No. 34,047

3 Claims. (Cl. 17—1)

1

My invention consists of new and useful improvements in the evisceration of butchered animals, an object of the invention being to provide a device of the character herewithin described whereby the weasand may readily be separated from the oesophagus prior to disembowelling.

A further object of the invention is to provide a device of the character herewithin described which provides means for grasping firmly the severed end of the weasand thereby facilitating the separation thereof from the oesophagus.

Another object of my invention is to provide a device of the character herewithin described whereby the weasand may be separated from the oesophagus while the carcass of the animal is travelling upon an overhead moving rail under which conditions the neck of the animal is relatively close to the floor thus making it impossible for the operator to manipulate the conventional implement in order to separate the weasand from the oesophagus.

Another object of my invention is to provide a device of the character herewithin described which may be actuated pneumatically, hydraulically, or mechanically.

A still further object of my invention is to provide a device of the character herewithin described which is economical to manufacture, and rapid in operation, thereby resulting in a substantial saving of time and labor.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a side elevational view of my device.

Figure 2 is a sectional view along the line 2—2 of Figure 1.

Figure 3 is a fragmentary view of my device as shown in the act of separating the weasand from the oesophagus.

In the drawings like characters of reference indicate corresponding parts in the different figures.

In the process of evisceration of animals it is necessary to ensure that the weasand is removed together with the stomach without rupture, otherwise there is the possibility of the stomach contents contaminating the flesh of the animal. The weasand, which passes through the neck to the stomach, is attached to the oeso-

2

phagus by means of fatty tissue and the like, and has to be separated therefrom before disembowelling is undertaken in order to prevent this possibility occurring.

5 The separation is accomplished by means of an elongated rod having a metal ring rigidly attached approximately at right angles to one end thereof which, with one hand, is slipped over the end of the weasand extending from the neck of the animal after it is decapitated. The end of the weasand is then grasped by the other hand and the rod forced downwardly into the neck cavity, thereby separating the weasand from the oesophagus.

10 Due to the extremely slippery nature of the weasand, considerable difficulty is experienced by the operator in maintaining a firm grasp thereon, and so considerable time is lost which affects substantially the efficiency of the modern meat packing plant.

15 Consequently in an endeavour to overcome the foregoing difficulties, I have designed my novel weasand separator, and upon reference to the accompanying drawings it will be observed that it consists of the following parts.

A piston rod 1 is positioned within the cylinder 2, actuated by compressed air or hydraulic fluid entering from a main supply via the nozzle 3. The flow of the piston actuating fluid is controlled by means of the trip lever 4 which actuates a valve (not illustrated) carried on the bracket 5, and is routed via the valve to the inlet conduit 6 situated substantially toward the rearward end of the cylinder.

30 The piston rod 1 carries the weasand separator component 7 on the distal end thereof to which is attached substantially at right angles the weasand separator ring 8. In this embodiment it will be seen that the ring is rigidly connected to the component 7 by means of the pin 9 on the perimeter thereof and is supported by the throat 10 which extends partially around the perimeter as clearly shown in Figure 2 of the accompanying drawings.

35 The ring 8 is substantially in alignment with the hand operated vise clamp 11 which is rigidly connected to the cylinder by means of the encircling sleeve 12. The vise clamp, which is of conventional construction, is provided with the serrated jaws 13, the relationship of which is controlled by the knurled screw 14 situated in the rear end of the clamp, and it will be appreciated that movement of the hand lever 15 downwardly in relation to Figure 1, will cause the jaws to

close and remain closed by virtue of the link and cam action 16.

Figure 3 of the accompanying drawings shows a fragmentary view of my device in action, and it will be appreciated that the weasand 17 has been passed through the ring 8 and inserted between the jaws 13 whereupon the clamp was closed. Fluid pressure is then supplied to the upper side of the piston rod by means of the lever 4 thereby extending the piston rod from the cylinder. This causes the ring to travel along between the weasand 17 and the oesophagus 18 thereby severing the adjoining tissue.

The piston rod can be returned to the retracted position of Figure 1 either by a compression spring (not illustrated) on the underside of the piston, or similar means.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What I claim as my invention is:

1. An eviscerating implement for separating the weasand from the oesophagus comprising in combination with a source of fluid power a cylin-

der, a piston therein, projecting therefrom at one end thereof, a weasand encircling ring on the exterior end of said piston, and a weasand clamp on the side of said cylinder having the jaws thereof directed towards said ring.

2. In the art of evisceration, means for separating the weasand from the oesophagus comprising in combination a cylinder, a piston therein, projected therefrom at one end thereof, a weasand encircling ring secured to said piston at a point on its perimeter and projecting at right angles therefrom, a weasand clamp on the side of said cylinder having the jaws thereof directed towards said ring, and a source of power for said piston and cylinder.

3. An eviscerating implement for separating the weasand from the oesophagus comprising in combination with a source of fluid power, a cylinder, a piston therein, projecting therefrom at one end thereof, a weasand encircling ring secured to said piston at a point on its perimeter and projecting at right angles therefrom, and a weasand clamp on the side of said cylinder having the jaws thereof directed towards said ring, said clamp and said ring being substantially in alignment one with the other.

WILLIAM JOHN HINCKS.
